UNITED STATES PATENT OFFICE.

ALBERT W. HYDE, OF NEWTON CENTRE, MASSACHUSETTS.

APPARATUS FOR TREATING VISCOUS ROCK FOR PAVING PURPOSES.

SPECIFICATION forming part of Letters Patent No. 447,711, dated March 3, 1891.

Application filed September 26, 1890. Serial No. 366,197. (No model.)

To all whom it may concern:

Be it known that I, ALBERT W. HYDE, of Newton Centre, in the county of Middlesex and State of Massachusetts, have invented 5 certain new and useful Improvements in Apparatus for Treating Viscous Rock for Paving Purposes, of which the following is a specification.

My invention relates to means for crushing 10 or grinding bituminous and other viscous rock; and it consists of an improved apparatus, comprising in its construction a preliminary crusher, which may consist of a pair or pairs of jaws, or a pair of rollers for breaking 15 the rock into fragments, a pair of rolls having corrugated or other suitably-formed surfaces, adjusted or gaged to grind or granulate the fragments received from the preliminary crusher, and a second set of rolls 20 adjusted or gaged to pulverize or finish the treatment of the material received from the first set of rolls, and suitable means for conveying the material from the preliminary crusher to the first set of rolls and from the 25 first to the second set of rolls.

My invention also consists of combining with the foregoing devices a heater for heating the material after it comes from the finishing-rolls.

My invention also consists of parts and 30 combinations of parts incidental to the foregoing, all as will more fully appear hereinafter.

Reference is to be had to the annexed drawings and to the letters of reference marked thereon, forming a part of this specification, the same letters designating the same parts or features, as the case may be, wherever they occur.

In the drawings, Figure 1 is a sectional side elevation of my improved apparatus. Fig. 2 is a vertical central sectional view of the preliminary crusher. Fig. 3 is a like view of a set of pulverizing-rolls and their adjuncts. Fig. 4 is a top plan view of a set of corrugated pulverizing-rolls. Fig. 5 is a longitudinal sectional view of the heater, the conveyer for supplying the same with material, and the finishing-rolls and their supplying means. Fig. 6 is a cross-sectional view of the heater and some of its adjuncts. Fig. 7 is an end view of the same. Fig. 8 is a side elevation

of a modified form of apparatus. Fig. 9 is a vertical sectional view of another modification.

In carrying out my invention I employ a crushing device A, capable of breaking viscous or non-friable rock—such, for instance, as bituminous rock or rock impregnated with mineral pitch.

In the drawings I have shown the device A as consisting of what is commonly known as a "Blake crusher," *a* designating the fixed jaw, *b* the movable jaw, and *c* the toggle-levers for operating the movable jaw.

d is the eccentric shaft, by which, through the medium of the pitman *f*, the toggle-levers are operated.

g is the rubber spring, which operates on the rod *h*, connected with the movable jaw *b* to open the jaws.

The material is fed through the preliminary crusher A, being operated upon by the jaws *a b* to crush or break it into fragments, and is conducted by any suitable conveyer to a set 75 of crushing or pulverizing devices B, consisting of a pair of rolls *i j*, having, preferably, corrugated surfaces and so arranged as that the ribs of one roll will operate in the grooves of the opposing roll, as is shown in Figs. 3 and 80 4, the said rolls being so gaged or set as to grind or granulate the fragmentary rock, whence it is conveyed by suitable contrivances to a set of finishing-rollers *k l*, the surfaces of which are corrugated, and if corrugated I 85 prefer that the corrugations should be of finer gage than those of the granulating or grinding rolls *i j*. The rolls *k* are so set or adjusted as to effect a practical pulverization of the granulated material.

In Fig. 5 I have shown an Archimedean screw *m*, as arranged to convey the pulverized material from the pulverizing-rollers *k l* to a heater consisting of a drum *n*, lined with a series of pipes *o*, to which steam, hot water, 95 or hot air or other gas may be conveyed through the supply-pipe *p*, provided with branch pipes *q*.

r designates leaves or strips of metal, connected with the lining-pipes *o* and extending 100 radially inward, which leaves serve as the heater is rotated to hold the material in one position for a longer time than would otherwise be the case in contact with the heated

pipes and to as thoroughly stir the material in the heater as may be necessary. The heater may be rotated by means of toothed wheels *s*, on the ends of a shaft *t*, driven by means of a belt (not shown) on pulley *u*. The toothed wheels *s* may engage teeth *v*, formed in the periphery of the drum *n*, which latter device may rest upon wheels or rollers *w*.

While the heater is shown in Fig. 5 as arranged in horizontal position, it will be in practice arranged so that the receiving end will stand upon a higher plane than the opposite end, in order that the material fed thereto by the screw *m* may gravitate to the opposite end and be discharged therefrom. I have shown the heater as mounted upon wheels *x*, so that it can conveniently be moved into and out of place with respect to the conveyer *m*, it being understood that the heater is a part of the apparatus which may or may not be used, according as to whether it is desired to make immediate use of the product or to pack or store it for future use.

In Fig. 1 the preliminary crusher *A*, the granulating device *B*, and finishing or pulverizing device *C* are shown as arranged upon the same horizontal plane, and the conveying devices between the crusher *A* and granulating device *B* and between the latter and the pulverizing device *C* are shown as consisting of an endless line of buckets *y*, which run over pulleys or sprocket-wheels *z*.

In Fig. 8 the devices *A*, *B*, and *C* are shown as arranged on different floors of a structure, the one above the other, the conveying devices consisting of chutes or pipes *a' b'* and hoppers *c' d'*, while in Fig. 9 the several devices *A*, *B*, *C* are shown as supported in a single frame *e'*, the conveying devices consisting of hoppers and connected pipes *f' g' h'*. The crusher *A* is shown in Fig. 9 as consisting of a pair of rolls *i' j'*, which may be supposed to be coarsely corrugated, and adjusted so as to affect the breaking of the rock into fragments. These various forms of construction and arrangement of devices are illustrated in order to show the changes which may be made in

my invention without departing from the nature or spirit thereof.

In Fig. 9 are shown scrapers or cleaning-fingers *k'*, pivoted at *l'*, with their operating ends resting against the face of the crushing, granulating, and finishing rolls, their opposite ends being weighted, as at *m'*. These contrivances serve to clear or free the surfaces of the rolls from material which may have a tendency to adhere thereto.

My invention is specially designed for the treatment of mineral pitch-bearing rock, such as what is commonly known as "bituminous rock," which is employed for paving purposes, and which is of a quite non-friable viscous nature and difficult of pulverization. By first fragmentizing the rock, then granulating it, and finally pulverizing it I am enabled to get a thoroughly-efficient and uniformly-fine product, which is not obtainable by other known means.

Having thus explained the nature of my invention and described a way or ways in which the same may be used, I declare that what I claim is—

1. In an apparatus for treating bituminous or other rock, the combination, with a preliminary crusher, an intermediate granulating device, and a pulverizer, of a heater and a conveyer to deliver the pulverized material to the heater, substantially as described.

2. In an apparatus for treating bituminous and other rock, the combination, with a preliminary crusher, an intermediate granulating device, and a pulverizer, of a heater, mechanism for revolving said heater, and mechanism for delivering the pulverized material to the heater, substantially as described.

In testimony whereof I have signed my name to this specification, in the presence of two subscribing witnesses, this 22d day of September, A. D. 1890.

ALBERT W. HYDE.

Witnesses:

ARTHUR W. CROSSLEY,
A. D. HARRISON.
